UNITED STATES PATENT OFFICE.

JOHN B. WINTER, OF LOUISVILLE, KENTUCKY.

DESIGN FOR A CHIMNEY-TOP CAP.

SPECIFICATION forming part of Design No. 16,754, dated June 22, 1886.

Application filed January 19, 1886. Serial No. 189,096. Term of patent 3½ years.

To all whom it may concern:

Be it known that I, JOHN B. WINTER, a citizen of the United States, residing at Louisville, in the county of Jefferson and State of Kentucky, have invented and produced a new and original Design for Chimney-Top Caps, of which the following is a specification, reference being had to the accompanying drawings, forming part thereof.

10 Figure 1 is a perspective view of my newly-designed chimney-top cap. Fig. 2 is a sectional view of the cap, taken as indicated by the dotted lines, showing the raised flue-flange, water-table, and protecting-flange below.

15 Heretofore chimney-top caps have been in use plain on the top, with small strips on the inner edges around the flue-opening, with a small flange on the under side, with the edges of the cap projecting slightly over the flange 20 below.

The leading features of my design consist in the cap A, which is slightly convex on the

top, with an ornamental raised flange, B, around the flue opening C, as shown in the drawings, and is also provided with a deep 25 flange, D, on the under side of the cap, which flange is ornamented, as shown at E in the drawings, with the edges of the cap projecting over the flange forming the water-table F, under the edges of which an ornamental drip- 30 flange, G, is arranged, as shown.

I claim—

The design for a chimney-top cap herein shown and described, the same consisting in the convex cap A, having an ornamental 35 raised flange, B, around the flue C, with a protecting-flange, D, on the under side of the cap A, having ornaments E on the face and ornamental drip-flange G under the edges.

JOHN B. WINTER.
